(57) **CLAIM**

The ornamental design for a stainless steel saucer, as shown and described.

DESCRIPTION

FIG. 1 is a perspective view of a stainless steel saucer showing my new design therefor;

FIG. 2 is a side elevational view thereof, all other sides being identical thereto;

FIG. 3 is a top plan view thereof;

FIG. 4 is a bottom plan view thereof; and,

FIG. 5 is a sectional view through the stainless steel saucer to better show the outward contour thereof.
